Attorney

UNITED STATES PATENT OFFICE.

ALBERT L. SHEARS, OF ST. LOUIS, MICHIGAN, ASSIGNOR OF ONE HALF TO
JOHN M. COMBS, OF HICKSVILLE, OHIO.

CENTER-BOARD FOR VESSELS.

SPECIFICATION forming part of Letters Patent No. 352,490, dated November 9, 1886.

Application filed June 17, 1886. Serial No. 205,478. (No model.)

To all whom it may concern:

Be it known that I, ALBERT L. SHEARS, a citizen of the United States of America, residing at St. Louis, in the county of Gratiot 5 and State of Michigan, have invented certain new and useful Improvements in Center-Boards for Vessels; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in center-boards for vessels, the object of the same being to provide a means whereby the angle of the center-board can be varied with respect to the hull of the vessel as 20 well as elevated or depressed.

In the accompanying drawings, which illustrate my invention, Figure 1 is a sectional view showing my improved center-board applied. Fig. 2 is a side view of the center- 25 board and well detached from the vessel, and Fig. 3 is a plan view.

A refers to the hull of the vessel, which is provided at a suitable point with a circular opening, *a*, through which the center-board 30 passes. Adjacent to this circular opening a well, B, which is circular in cross-section is attached to the inner side of the bottom and to the deck of the vessel, the lower portion of said well being provided with an outwardly- 35 projecting flange, *b*, by means of which it can be tightly secured to the bottom boards of the hull. This well, if desirable, can extend upwardly through the deck.

C refers to an inner well, which is securely 40 journaled in any suitable manner to the outer well, B, so that it can be rotated therein. This inner well is provided at its upper and lower ends with heads *d* and *e*, said heads being provided with transverse slots *f*, through which 45 the center-board F will pass. The heads *d* and *e* are provided adjacent to this slot, through which the center-board passes, with guide-rollers *g*, which are attached to the heads in any suitable manner, and the upper head, *e*, is 50 provided with supports and journals for a pinion, *h*, provided with a crank-handle, *h'*,

said pinion engaging with a rack-bar, I, which is attached to the edge of the center-board.

The center-board F can be adjusted vertically within the well C by turning the ratchet-wheel, and when it is desired to turn the same at an angle the handle F', attached to the upper portion of the center-board, can be turned. When this is done, the dog or locking device *i*, attached to the upper head, *e*, of the inner well, will engage with notches or projections in the upper edge of the outer well, so as to hold the same in the position to which it may be adjusted.

By means of the device hereinbefore described the center-board can be changed so as to occupy a position at an angle with the hull and at right angles with the leeway of the vessel, so as to prevent to a great extent leeway when the wing is on the quarter. This center-board may also be changed to occupy a position parallel with the transverse line through the hull of the vessel, and when in such a position will act as a drag or brake, so as to prevent to a great extent forward movement of 75 the vessel.

When the center-board is placed at an angle with the longitudinal line through the vessel, the same, when the vessel is under sail, will prevent the keeling of the vessel to a great degree, the force of the water against the board, when it is at an angle, tending to throw the vessel on its keel, in comparison to the force of the wind.

I do not wish to limit myself to the precise 85 construction shown in the drawings; but reserve the right to vary the appliances and means for rotating and vertically adjusting the board.

I claim—

1. In combination with the hull of a vessel, a circular casing or well attached thereto, an inner cylinder, C, attached to said well and journaled so as to rotate therein, said inner cylinder carrying a vertically-adjustable center-board, substantially as shown, and for the purpose set forth.

2. In a vessel, an outer cylindrical well, B, having an inner cylinder journaled thereto so as to rotate within the same, a center-board, F, attached to the inner cylinder and provided with a rack and pinion for vertically adjust-

ing the same, substantially as shown, and for the purpose set forth.

3. The combination, in a center-board for vessels, of an outer cylinder, B, rigidly attached to the hull, an inner cylinder, C, journaled thereto so as to be capable of a rotary movement, a dog for locking said cylinders to each other against rotary movement, a center-board, F, provided with a rack-bar and handles F', a pinion attached to the inner cylinder for vertically adjusting the center-board, substantially as shown, and for the purpose set forth.

4. In combination with a center-board for vessels, the outer cylinder, B, provided at its upper edge with notches, an inner cylinder, C, journaled within the outer cylinder so as to be

capable of a rotary movement, said inner cylinder being provided with heads d and e, with transverse slots f and guide-rollers g, a rack 20 attached to the center-board, a pinion with crank-handle attached to the upper head of the inner cylinder for adjusting vertically the center-board, and a dog, i, for locking the cylinders against rotary movement, the parts being organized substantially as shown, and for the purpose set forth.

In testimony whereof I affix my signature in presence of two witnesses.

ALBERT L. SHEARS.
